E. A. DEWALD

JAR CLOSURE

Filed May 12, 1924

UNITED STATES PATENT OFFICE.

EDWARD A. DEWALD, OF MASSILLON, OHIO.

JAR CLOSURE.

Application filed May 12, 1924. Serial No. 712,694.

To all whom it may concern:

Be it known that I, EDWARD A. DEWALD, a citizen of the United States, residing at Massillon, in the county of Stark and State 5 of Ohio, have invented certain new and useful Improvements in Jar Closures, of which the following is a specification.

This invention relates to jar covers and more particularly to a cover adapted for use 10 upon the well known "Mason" fruit jar.

Jars of this type are provided with an annular flange spaced from the mouth of the jar, a rubber packing ring being arranged to be clamped between said flange 15 and the usual screw cap.

Owing to frequent irregularities in this flange, as well as in the edge of the screw cap, difficulty is frequently experienced in obtaining an air-tight seal with the use of 20 the usual screw cap; and the moving contact of the edge of such a cap tends to cut or displace the rubber packing ring.

The object of the present improvement is to provide a jar closure which eliminates 25 the above difficulties and forms an air-tight seal between the cover and the mouth of the jar; the closure being adapted to be applied to the ordinary Mason jar without any change in the construction thereof. A further object of the improvement is to provide 30 a closure which may be easily and readily applied to or removed from the jar and which will be tightly retained in place when applied to the jar.

The above and other objects are attained 35 by providing a parabolic spiral groove having a continuous pitch, in the top of the cover; and by providing a U-shaped yoke having a diametric raceway containing a ball adapted to operate in the spiral groove 40 and provided with engaging flanges upon its legs adapted to engage under the annular flange upon the neck of the jar.

An embodiment of the invention thus described in general terms, is illustrated in the accompanying drawing, in which—

Figure 1 is a vertical sectional view of the upper portion of a Mason jar, provided with the improved closure, showing the same in the initial position;

Fig. 2, a side elevation of the same, showing the closure in the locked position;

Fig. 3, a top plan view of the spirally grooved cover;

Fig. 4, a top plan view of the yoke;

Fig. 5, a section on the line 5—5, Fig. 2; and

Fig. 6, a transverse section through the yoke on the line 6—6, Fig. 4.

Similar numerals refer to similar parts throughout the drawing.

A Mason type of fruit jar is illustrated at 1 and provided with the usual exteriorly threaded neck 2, having the annular flange 3 below the threaded portion, and terminating in an annular rim 4 surrounding the mouth 5. A rubber packing ring 6 is provided for such jars, which is placed around the neck, upon the flange 3 when an ordinary screw cover is used.

The present jar closure includes the cover 5^a which is preferably molded glass having the annular boss 6^a adapted to extend into the mouth of the jar to prevent an air space between the contents of the jar and the cover, and provided with the annular shoulder 7 arranged to seat upon the rim 4 of the mouth; and for sealing the jar, the ordinary rubber packing ring 6 is preferably placed upon the rim and forms a cushion for the cover shoulder.

A parabolic spiral groove 9 is formed in the top of the cover 5^a, and, as best shown in Fig. 1, this groove has a continuous inclination from the periphery to the middle 85 of the cover; the inner end of the groove being considerably higher than the outer end thereof.

For the purpose of clamping the cover upon the neck of the jar, a yoke 10, preferably stamped from a strip of open hearth drawn steel, is provided. This yoke comprises the central channel portion 11, the lower edges of which are slightly inturned as at 12 to form a raceway and retain the ball 13. Stop lugs 16 are formed at each end of the ball race to limit the movement of the ball in each direction. The depending leg portions 14 are preferably flared in width at their lower ends, and are provided with the engaging L-flanges 15 preferably concaved and adapted to engage and operate under the annular flange 3 of the jar.

A pair of ears 17 is provided in the an-

gles at each side of the flange 15 and arranged to substantially engage the periphery of the annular flange 3 when the closure is in the clamped position, as shown in Figs.

5 2 and 5.

For the purpose of strengthening the legs 14 of the yoke, a rib 18 is formed in each leg, terminating in the curved upper end 19, which merges into the body portion 10 of 10 the yoke, and in the curved lower end 20 extended beneath the flange 15.

In placing the closure upon the jar, the glass cover 5^a is first placed over the mouth of the jar, as shown in Fig. 1, the rubber 15 ring 6 being located between the annular shoulder 7 of the cover and the mouth of the jar.

The ball 13 is then moved to the end of 20 the ball race 11 in the yoke, and the yoke is slipped sideways over the neck of the jar until it assumes a diametric position, as shown in Fig. 5, the ball engaging the outer end portion of the spiral groove 9 in the cover.

25 It should be noted that, as shown in Fig. 1, when the yoke is first slipped over the neck of the jar, it is lowered, permitting the ears 17 upon the leg flanges to pass beneath the annular flange 3 of the jar.

30 The yoke is then raised until the flanges 15 upon the legs thereof engage the under side of the annular flange 3 of the jar, the ears 17 engaging the periphery of the annular flange 3, and preventing the yoke 35 from being displaced sideways. The yoke is then rotated around the neck of the jar in a direction to cause the ball 13 to travel toward the inner end of the spiral groove 9.

40 As the ball reaches the inner higher end of the spiral groove, as shown in Fig. 2, the cover will be tightly clamped upon the mouth of the jar, compressing the rubber ring 6 between the shoulder 7 of the cover and the mouth 4 of the jar, forming an air-tight seal at the joint.

45 The yoke will thus be frictionally held in clamped position, preventing accidental turning movement of the same, while the ears 17 prevent side movement of the yoke with reference to the jar.

50 Due to the considerable length of the spiral groove in proportion to the slight inclination thereof toward the inner end, it is evident that the rotation of the yoke causing the ball to travel toward the highest point of the groove, develops the power to 55 the maximum.

60 It will be understood that the form of the invention illustrated is intended to show the application of the improved cover upon a Mason jar as now in common use. However, it is intended that new jars manufactured especially for use with the improved cover will not have the elongated, 65 threaded neck. This will permit the cover

to be provided with considerably shorter legs than illustrated, the construction being otherwise the same as illustrated.

I claim:

1. In combination with a jar having an annular flange around its neck portion, a closure including a cover arranged to engage the mouth of the jar and having a spiral groove in its upper face, a U-shaped yoke provided with a raceway and having L-shaped legs for engagement with the flange upon the jar, and a ball in the raceway for operating in said spiral groove. 70

2. In combination with a jar having an annular flange around its neck portion, a closure including a cover arranged to engage the mouth of the jar and having a spiral groove in its upper face, a U-shaped yoke provided with a raceway and having flanged legs for engagement with the flange upon the jar, and a ball in the raceway for operating in said spiral groove. 75 80

3. In combination with a jar having an annular flange around its neck portion, a closure including a cover arranged to engage the mouth of the jar and having a spiral inclined groove in its upper face, a U-shaped yoke provided with a raceway and having flanged legs for engagement with the flange upon the jar, and a ball in the raceway for 90 operating in said spiral groove. 95

4. In combination with a jar having an annular flange around its neck portion, a closure including a cover arranged to engage the mouth of the jar and having a spiral inclined groove in its upper face, a U-shaped yoke provided with a raceway and having flanged legs for engagement with the flange upon the jar, a ball in the raceway for operating in said spiral groove, and means for 100 limiting the movement of the ball in the raceway. 105

5. In combination with a jar having an annular flange around its neck portion, a closure including a cover arranged to engage the mouth of the jar and having a spiral inclined groove in its upper face, a U-shaped yoke provided with a raceway and having flanged legs for engagement with the flange upon the jar, a ball in the raceway for operating in said spiral groove, and means for preventing sideways displacement of the yoke. 110 115

6. In combination with a jar having an annular flange around its neck portion, a closure including a cover arranged to engage the mouth of the jar and having a spiral inclined groove in its upper face, a U-shaped yoke provided with a raceway and having flanged legs for engagement with the flange upon the jar, a ball in the raceway for operating in said spiral groove, and lugs upon the flanged legs of the yoke for engagement with the periphery of the annular flange upon the jar. 120 125 130

7. In combination with a jar having an annular flange around its neck portion, a closure including a cover arranged to engage the mouth of the jar and having a spiral inclined groove in its upper face, a U-shaped yoke provided with a raceway and having flanged legs for engagement with the flange upon the jar, a ball in the raceway for operating in said spiral groove, and an annular boss upon the cover for insertion into the mouth of the jar. ¹⁰
